CAN HANDLING MACHINE

Edwin Earl Hanson, Snohomish, Wash.

Application July 16, 1942, Serial No. 451,175

9 Claims. (Cl. 198—211)

The invention aims to provide a new and improved machine for use in canneries to receive sealed cans of vegetables, fruits, etc. as they come from the seamers, and to stand them on end in orderly rows in cooling trays or the like, for cooling preparatory to labeling and packing.

In carrying out the above end, a further object is to provide a machine of the class described having a novel rotatable conveyor provided with trays which receive the cans at a receiving station, convey them to a dumping station, and here dump them on end into a cooling tray or the like.

Another object is to make novel provision whereby the conveyor will not turn during filling of any of the trays with cans but will turn immediately after such filling, moving the filled tray to the dumping station and positioning the next empty tray at the receiving station.

Yet another object is to make novel provision whereby the cans left standing on a track which conducts them to the rotatable conveyor, cannot interfere with turning of said conveyor when any of its trays has been filled.

A still further object is the provision of a simple, inexpensive, efficient and durable machine which will operate automatically to receive, convey and dump the cans.

With the foregoing and minor objects in view, the invention resides in the novel subject matter hereinafter described and claimed, description being accomplished by reference to the accompanying drawings.

Figure 1 is a side elevation partly in section as indicated by line 1—1 of Fig. 2, portions of the two inclined track braces being broken away.

Figure 2 is an end elevation partly in section as indicated by line 2—2 of Fig. 1, one of the trays of the rotatable conveyor being considered as almost completely filled with cans (see Fig. 1).

Figure 3 is a fragmentary end view showing the tray of filled cans moved to dumping position and illustrating the cans in the act of being dumped on end into a cooling tray.

Figure 4 is a fragmentary end elevation similar to a portion of Fig. 2 but showing the rotatable conveyor turned one step from the position shown in Fig. 2 to present the next tray at the can-receiving station, it being considered that some of the cans have already entered the tray.

Figure 5 is a view similar to Fig. 4 but illustrating the conveyor driving pawl and its carrier on their receding stroke, the pawl being latched against further engagement with the rotary conveyor until required.

Figure 6 is a detail sectional view on line 6—6 of Fig. 5, illustrating the manner in which the pawl is latched against further operation until required.

Figure 7 is a fragmentary perspective view illustrating the manner in which the cans left standing on the feed track are pushed back slightly when the conveyor with a filled tray starts to move, preventing the track-supported cans from interfering with conveyor turning.

Figure 8 is a fragmentary perspective view illustrating the timing mechanism which effects release of the latched pawl (Figs. 5 and 6) when the conveyor is next to be turned.

Figure 9 is a fragmentary perspective view showing one end of one of the can-receiving trays of the rotatable conveyor.

A rotatable conveyor 10 is shown having trays 11 for receiving cans 12 from an inclined feed track 13 at a receiving station 14 (Figs. 1, 2 and 4), for conveying the cans to a dumping station 15 (Fig. 3) and for dumping them on end in orderly rows at said dumping station, the dumped cans being received in a cooling tray, basket or the like 16. This member 16 may be supported in any suitable way and advanced the proper distance after dumping of each row of cans into the same. It is shown supported on a roller conveyor 17 and as the details of the mechanism which advance it, form no parts of the present invention, the advancing mechanism has not been illustrated.

In the present disclosure, the conveyor 10 includes a horizontal shaft 18 rotatably mounted in suitable bearings of end frames 19. Two end wheels or disks 20 and 21 are secured to the shaft 18 and the can-receiving trays 11 extend between said disks or wheels and are pivotally supported thereby, the pivotal supports preferably consisting of rods 22 secured to said disks or wheels and passing through openings in blocks 23 on the trays, the pivotal mountings of said trays permitting them to tilt from the can-receiving position shown for example in Fig. 2, to the can-dumping position shown in Fig. 3, and also permitting return of the trays into position to receive other cans. In the present disclosure arcuate tracks 24 are secured to the end frames 19 as shown at 25 and are braced thereto as at 26, said tracks being cooperable with the end-most blocks or shoes 23 of the trays 11 to properly position the trays from which the cans have been dumped, to again receive cans from the feed track 13 as illustrated in Fig. 2. These tracks 24 are of such length that they will hold the

trays 11 against dumping after they have been filled, until they reach the dumping station 15, as will be clear by comparing Figs. 2 and 3.

A one-way driving mechanism is shown for turning the conveyor 10 step-by-step in one direction to successively position its trays at the receiving and dumping stations 14 and 15 respectively. In the present disclosure, the peripheral edge of the wheel or disk 20 is formed with notches 21 which correspond in number and spacing to the trays 11, and for cooperation with said notches, I provide a driving pawl 28 to which proceeding and receding movements are imparted by means of a pawl carrier 29 which is connected with a reciprocatory pitman 30 actuated by any appropriate means. The pawl carrier 29 is preferably in the form of an oscillatory arm pivotally mounted upon the shaft 18, and the stroke of this arm is of course such that when the pawl 28 is in one of the notches 21 (see Fig. 2) with the lowermost tray 11 filled with cans, the movement of said pawl and carrier will turn the conveyor 10 sufficiently to move the filled tray 11 to and past the dumping position 15 (Fig. 3) and position the next empty tray 11 (Fig. 4) at the receiving station 14. It is of course essential that this last mentioned tray remain at the receiving station 14 until it is entirely filled with cans, and I have, therefore, made provision whereby the pawl 28 is temporarily held against engagement with the next notch 21 of the wheel 20 when said pawl is returned to its uppermost position by the carrier arm 29. Thus, when the arm 29 makes its next proceeding stroke, if the tray 11 has not been completely filled with cans, the pawl 28 will be prevented from turning the conveyor 10. Provision, however, is made, controlled by the cans entering the machine, for releasing the pawl 28 and thus permitting it to again function when the tray 11 has been completely filled.

In the present disclosure, I have provided a latch lever 31 on the pawl-carrying arm 29 for latching said pawl in the inoperative position shown in Figs. 5 and 6, said latch lever being urged toward its pawl latching position by a suitable spring 32. The latch lever 31 is formed with a pawl-engaging nose 33 which is in readiness to engage the pawl 28 while said pawl is turning the conveyor 10 from the position of Fig. 2 to that of Fig. 4. This nose 33, however, then abuts a portion of the pawl 28 as will be clear from the dotted lines in Figs. 2 and 4. However, as soon as the return stroke of the pawl 28 starts (Fig. 5) and said pawl moves out of the notch 21 (see same view), the latch lever 31 immediately moves to pawl-holding position under the influence of the spring 32, as clearly shown in Figs. 5 and 6. When the latch lever 31 thus holds the pawl 28, this pawl cannot again engage a notch 21 of the wheel 20 until the latch lever has been released. Thus, the carrier 29 may continue its proceeding and receding strokes without turning the conveyor 10 until release of the latch lever 31 has been effected, and such release occurs only when the tray 11 being filled, has been completely filled, as will be explained below.

A latch-releasing lever 34 is fulcrumed on one of the end frames 19 and is provided with a curved upper end 35 cooperable with the inner end of the latch lever 31, and whenever the lower end of said lever 34 is pushed outwardly (see Fig. 1) said lever swings the latch lever 31 to pawl-releasing position as also illustrated in Fig. 1. Thus, upon its next proceeding stroke,

the pawl 28 may function to turn the conveyor 10 the next step.

Rotatably mounted on one of the end frames 19 near the lower end of the latch-releasing lever 34, is a peripherally toothed timing wheel 36 having a lateral lug 37 to outwardly push the lower end of the latch-releasing lever 34 at the proper time to effect release of latch lever 31 (see Fig. 1). One-way driving means is provided for the timing wheel 36, said driving means being actuated by the cans 12 entering any tray 11, whereby said timing wheel is turned to the proper extent to cause the lug 37 to effect release of the latch lever 31 only when the tray has been completely filled. In the present showing, a spring pawl 38 coacts with the teeth of the timing wheel 36, said spring pawl being carried by a vertically swingable arm 39 which is pivoted at 40 to the adjacent end frame 19, said arm 39 having a roller or the like 41 which engages the cans entering the machine as will be clear from Figs. 2, 4 and 8. Each time the arm 39 is swung upwardly by a can 12 passing under the roller 41, the pawl 38 turns the timing wheel 36 one tooth, and a suitable dog 42 may be employed to hold said timing wheel against retrograde turning as the pawl 38 drops with the arm 39 when the can passes. The ascent of the pawl 18 effected by the last can 12 entering the tray 11, turns the timing wheel 36 the final step required to cause its lug 37 to outwardly push the lower end of the latch-releasing lever 34, thus causing this lever to release the latch lever 31 from the pawl 28, and it will be recalled that this latch lever was holding said pawl in the inoperative position of Figs. 5 and 6, while filling of the tray 11 took place. With the latch lever 31 released, the next proceeding stroke of the carrier 29 and pawl 28, will cause said pawl to engage the uppermost notch 21 of the wheel 20, whereupon the conveyor 10 will be turned another step. During this step, the cans in the filled tray dump into the cooling tray or the like 16 as seen in Fig. 3, and the dumped tray then moves beyond this position as the next tray arrives at the receiving station 14 to be filled.

It will be seen from the foregoing that a novel and advantageous automatic structure has been provided for receiving the cans when any tray 11 arrives at the receiving station 14; for conveying the filled tray to the dumping station 15 (Fig. 3), for dumping the cans in an orderly row into a receiving tray or the like 16 for cooling, and for presenting the next empty tray to the receiving station 14 for filling. It will also be observed that the cans entering the machine control the one-way driving means for the rotary conveyor 10 so that the latter will not be driven until any tray being filled has been completely filled.

In order to prevent the cans left standing on the track 13, or rather the innermost of these cans, from interfering with turning of the conveyor 10 when any tray 11 has been completely filled, novel provision is made. The disk or wheel 20 is of course formed with circumferentially spaced openings 43 which successively align with the track 13 in order that the cans may enter the tray 11 at the receiving station. The rear edges of these openings are provided with toes 44 which push back the track-supported cans (see Fig. 7) when the conveyor 10 with a loaded tray starts to turn, and it is thus insured that the track-supported cans cannot cause any jamming of the machine. The toe 44 enters between the downwardly converging sides of the last can which enters the tray 11 and the next can left standing on

the track 13, and crowds the latter can and others on the track back sufficiently to permit free rotation of the conveyor 10. Whenever this conveyor has been turned one complete step and the pawl 28 starts on its receding stroke, the friction of the shaft 18 in its bearings or other suitable medium may be relied upon to prevent any retrograde turning of the conveyor 10.

From the foregoing taken in connection with the accompanying drawings, it will be seen that novel and advantageous provision has been made for carrying out the objects of the invention, and while preferred features have been illustrated, attention is invited again to the possibility of making variations within the scope of the invention as claimed.

I claim:

1. A can handling machine comprising a supporting frame, a rotatable wheel-like can conveyor mounted on said frame for rotation about a single horizontal axis, said conveyor having circumferentially spaced trays into which the cans roll at a receiving station and by which the cans are conveyed to a dumping station, said trays being pivotally mounted on axes parallel with the axis of rotation of the conveyor to permit them to dump the cans on end at said dumping station, means for turning said conveyor in one direction step-by-step to successively present said trays at said receiving and dumping stations, and means for holding said trays against dumping while moving from said receiving station to said dumping station, permitting said trays to tilt to can-dumping position at said dumping station, and for restoring said trays to can-receiving position as they move from said dumping station to said receiving station.

2. A structure as specified in claim 1; said conveyor turning means having a controlling element actuated by the cans rolling into the machine for bringing said turning means into operation only when the tray at said receiving station has been filled.

3. A can handling machine comprising a supporting frame, a rotatable can conveyor mounted on said frame and having circumferentially spaced trays for receiving the cans at a receiving station, conveying them to a dumping station and dumping them at said dumping station, said rotatable conveyor being provided with a driving wheel, a one-way wheel-driving device for engagement with said wheel to turn said conveyor step by step as required, a proceeding and receding carrier for said wheel-driving device, means for holding said wheel-driving device temporarily against further operation after it has turned said wheel to present a tray at said receiving station, and means actuated by the cans being handled for releasing said holding means only when the tray at said receiving station has been filled.

4. A can handling machine comprising a supporting frame, a rotatable can conveyor mounted on said frame and having circumferentially spaced trays for receiving the cans at a receiving station, conveying them to a dumping station and dumping them at said dumping station, said rotatable conveyor being provided with a driving wheel having notches circumferentially spaced to the same extent as said trays, a pawl for successive cooperation with said notches to drive said wheel step by step and thereby turn said conveyor as required, a proceeding and receding carrier on which said pawl is mounted, a latch on said carrier for latching said pawl in inoperative position each time it leaves a notch of said wheel

after turning the latter to position a tray at receiving position, and means actuated by the cans being handled for releasing said latch only when the tray at said receiving station has been filled.

5. A can handling machine comprising a supporting frame, a rotatable can conveyor mounted on said frame and having circumferentially spaced trays for receiving the cans at a receiving station, conveying them to a dumping station, said rotatable conveyor being provided with a driving wheel, a one-way wheel-driving device for engagement with said wheel to turn said conveyor step by step as required, a proceeding and receding carrier for said wheel-driving device, means for holding said wheel-driving device temporarily against further operation after it has turned said wheel to present a tray at said receiving station, a releasing member for said holding means having a portion to be pushed to effect release of said holding means, a timer wheel rotatably mounted on the aforesaid frame and having a lug to push said portion of said releasing member each time said timer wheel is rotated a full revolution from a predetermined position, and a one-way driving device for turning said timer wheel step by step, said driving device for said timer wheel having an actuating member positioned to be operated once by each can entering the tray at said receiving station, whereby the total operations of this driving device during tray filling will turn said timer wheel a full revolution and cause its lug to effect release of the aforesaid holding means, permitting the aforesaid driving device for said conveyor driving wheel to function.

6. A can handling machine comprising a supporting frame, a rotatable can conveyor mounted on said frame and having circumferentially spaced trays for receiving the cans at a receiving station, conveying them to a dumping station, said rotatable conveyor being provided with a driving wheel having notches circumferentially spaced to the same extent as said trays, a pawl for successive cooperation with said notches to drive said wheel step by step and thereby turn said conveyor as required, a proceeding and receding carrier on which said pawl is mounted, a latch on said carrier for latching said pawl in inoperative position each time it leaves a notch of said wheel after turning the latter to position a tray at receiving position, a releasing lever for said latch mounted on the aforesaid frame and having a sliding contact with said latch, said releasing lever having an end to be pushed to effect release of said latch, a timer wheel rotatably mounted on the aforesaid frame and having a lug to push the aforesaid end of said latch releasing lever each time said timer wheel is rotated a full revolution from a predetermined position, and a one-way driving device for turning said timer wheel step by step, said one-way driving device having an actuating member positioned to be operated once by each can entering the tray at said receiving station, whereby the total operations of said one-way driving device during tray filling will turn said timer wheel a full revolution and cause its lug to effect release of said latch, permitting the aforesaid pawl to engage a notch of the conveyor driving wheel the next time the pawl carrier moves on its proceeding stroke.

7. A can handling machine comprising two horizontally spaced axially aligned wheels and

means rotatably mounting said wheels, can-receiving trays extending from one of said wheels to the other, and spaced apart circumferentially thereof, said trays being pivotally mounted to tilt from a receiving position to a dumping position, a track along which the cans roll to the outer side of one of said wheels, said one wheel having openings aligned with said trays to permit the cans to roll into and fill any tray when it is presented at a receiving station in alignment with said track, means for holding each tray in can-receiving position while at said receiving station and for permitting the filled tray to tilt to said dumping position when moved beyond said receiving station to a dumping station, and means for turning said wheels step by step to successively position said trays at said receiving station and said dumping station, said wheel-turning means having a controlling element actuated by the cans entering the tray at said receiving station for bringing said means into operation only when this tray has been filled.

8. A structure as specified in claim 7; said means for holding each tray in can-receiving position and for permitting the filled tray to tilt to dumping position consisting of a fixed arcuate track and shoes on said trays slideable along said track as the wheels and trays are turned.

9. In a can handling machine, a rotatable conveyor and means for turning it step by step, said conveyor having means to receive rows of cans and having an end wheel formed with openings through which the cans enter, a track along which the cans roll to said wheel for entrance through any opening aligned with said track, and a toe on the rear edge of each of said openings to move between the lower portion of the last can entering through the opening and the lower portion of the adjacent can left standing on said track, to force the latter back slightly and prevent it from interfering with turning of the conveyor.

EDWIN EARL HANSON.
